UNITED STATES PATENT OFFICE

JASON A. FITCH AND EDWARD ALBERT PURNELL, OF YOUNGSTOWN, OHIO, ASSIGNORS
TO THE GENERAL FIREPROOFING COMPANY, OF YOUNGSTOWN, OHIO, A CORPORATION OF OHIO

DESK ATTACHMENT

Application filed March 24, 1930. Serial No. 438,563.

This invention relates to a desk attachment in the form of a cabinet or so-called operator's case having compartments to receive different articles such as files and the like, and the general object of the invention is to provide a novel means to enable quick and easy attachment of the case to a desk and equally facile detachment of the case from a desk.

10 Another object of the invention is to provide means for attaching a case to a desk which means does not require screws or similar fastening elements and which will hold the case firmly secured to the desk for ready 15 detachment therefrom.

A further object of the invention is to provide a means for the purpose stated which is of simple, inexpensive construction and capable of quick and easy manipulation, and 20 which is thoroughly reliable and efficient in use.

With the foregoing and other objects in view, the invention consists in the novel features of construction, combination and 25 arrangement of parts as will be hereinafter more fully described, illustrated in the accompanying drawings, and defined in the appended claims.

In the drawings, wherein like characters 30 of reference denote corresponding parts in the different views:—

Figure 1 is a front elevation of a portion of a desk and of an operator's case, showing the latter attached to the former in accordance with the present invention.

Figure 2 is an enlarged section on the line 2—2 of Fig. 1.

Figure 3 is an enlarged vertical section illustrating the details of the present case 40 attaching means; and

Figure 4 is a side elevation of the operator's case.

Referring to the drawings in detail, A designates generally a portion of a desk and 45 B the present cabinet or operator's case which is adapted to be detachably secured against a side of the desk as illustrated in Fig. 1.

Preferably the case B is divided by vertical and horizontal partitions 10 and 11, respectively, into a number of different com-

partments suitable for the reception of various articles such as files and the like, and the top thereof preferably is formed to support a transcribing machine case designated generally as 12, but it will be understood, of course, that said case B may be of any other construction desired.

Hinged as at 13 to one side of the case B, near the top thereof, is a hook member designated generally as 14 for engagement with a top portion of the desk A to secure the case B thereto, while secured to the same side of said case, near the bottom thereof, is a member 15 for engagement with a side portion of the desk to hold the bottom portion of the case B properly spaced from the desk.

Either a plurality or only a single hook member 14 may be provided, the only essential in this respect being that if only a single hook member is provided it shall be of sufficient length to prevent forward or backward tilting movement of the case B, and that if two or more hook members are provided they shall be spaced sufficiently far apart to accomplish the same purpose.

A single elongated hook member 14 is illustrated in the present instance and same has been shown of a particular shape for cooperation with a desk of the particular construction shown. It is to be understood, however, that the shape of the hook member may be modified to adapt same for cooperation with desks of other constructions.

In general, the hook member 14 is of U-shape and inclusive of a straight portion or arm 16 of suitable length extending from the hinge pintle 13, a straight portion or arm 17 forming a continuation of the portion 16 at right angles thereto, and offset inwardly at a point remote from the portion 16 as indicated at 18, and a straight portion or arm 19 forming a continuation of the portion 17 and disposed parallel to the portion 16.

The desk A illustrated in the present instance is of known sheet metal construction and consists essentially of a body portion designated generally as 20 and a top portion designated generally as 21, the former being inclusive of a side or end panel designated as 22 and the latter being inclusive of a marginal

portion extending outwardly a short distance beyond said panel as indicated at 23.

As is usual in a desk of the type shown, the marginal portion 23 of the top 21 is of hollow construction and includes a flange or lip 24 which extends inwardly from the bottom of the edge forming vertical wall 25 of the top and terminates in spaced relation to the plane of the panel 22. This being the only 10 essential insofar as the present invention is concerned, and since the structural details of different desks of the type shown may vary in many respects, further description of the specific desk structure illustrated in the present instance is deemed to be unnecessary.

In view of the foregoing it is believed that the manner of attaching the case B to the desk A will be readily understood. In explanation, however, it may be stated that 20 normally the hook member 14 assumes a position with the arm 16 thereof disposed against the side of the case and the arm 19 thereof disposed outermost with its free edge portion facing upwardly. With said hook member 25 in this position the case is manipulated to align the arm 19 with the space between the inner edge of the desk top lip 24 and the side of the desk and the entire case then is moved upwardly to cause the arm 19 to enter the 30 hollow marginal portion of the desk top. At the same time the hook member 14 is swung upwardly relative to the case to cause the arm 19 to swing inwardly toward the case and to assume a horizontal position, which 35 manifestly results in the arm 17 assuming a vertical position. Thus, upon completion of this operation, which may be facilitated by properly manipulating the case B in a manner which is evident, the arm 19 of the hook member 40 is disposed above the lip 24 and the arm 17 of said hook member is disposed against the outer face of the panel 22 of the desk. If now the case is released the weight thereof obviously will be supported by the lip 24 of the desk top through the instrumentality of the hook member 14, and accidental disengagement of the case from the desk will 45 effectively be prevented by reason of the member 15 engaging the panel 22 and limiting swinging movement of the lower end portion of the case inwardly towards the desk and by 50 reason of the arm 17 of the hook member engaging said panel and holding the arm 19 of said hook member against sliding off of 55 the lip 24.

To detach the case from the desk it only is necessary to swing the lower end portion of the case away from the desk and at the same time raise the case and swing the hook member 14 downwardly, and then lower the case 60 and hook out of engagement with the desk top.

By particular reference to Fig. 3 of the drawings it will be observed that the desk top 65 21 is inclusive in the present instance of a

wall 26 disposed inwardly with respect to the wall 25 but outwardly with respect to the panel 22. It is for this reason that the offset 18 is provided in the arm 17 of the hook member 14, said offset being adapted to receive or accommodate the wall 26 when the hook member is positioned as shown in Fig. 3. Otherwise, that is, in the absence of the wall 26, or if said wall were disposed flush with or inwardly of the panel 22, the offset 18 might be 75 eliminated.

If desired the spacing member 15 and the arm 17 of the hook member 14 may be faced with felt or other suitable material to avoid marring of the desk surfaces with which these parts contact, and in this connection it will be observed that by reason of the present attaching means it is unnecessary to modify the desk structure in any way in order to effect attachment of the case thereto.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

We claim:

1. An attachment for a desk of the type in which the desk top includes a hollow marginal portion comprising a vertical edge wall and a bottom wall extending inwardly from said edge wall and terminating in spaced relation to the side of the desk, said attachment comprising a case and a substantially U-shaped hook member pivoted at one end to said case for detachable interfitting engagement with the hollow marginal portion of the desk top, said hook member having a terminal arm for insertion into the hollow marginal portion of the desk top to rest upon the bottom wall of said top portion thus to support the weight of the case from said bottom wall.

2. An attachment for a desk of the type in which the desk top includes a hollow marginal portion comprising a vertical edge wall and a bottom wall extending inwardly from said edge wall and terminating in spaced relation to the side of the desk, said attachment comprising a case and a substantially U-shaped hook member pivoted at one end to said case for detachable interfitting engagement with the hollow marginal portion of the desk top, said hook member having a terminal arm for insertion into the hollow marginal portion of the desk top to rest upon the bottom wall of said top portion thus to support the weight of the case from said bottom wall, said hook member further having a medial portion for engagement with the side of the desk when said terminal arm is operatively engaged with said bottom wall.

3. An attachment for a desk of the type in which the desk top includes a hollow marginal portion comprising a vertical edge wall and a bottom wall extending inwardly from said edge wall and terminating in spaced relation to the side of the desk, said attachment comprising a case, and a hook member carried by said case for detachable interfitting engagement with the hollow marginal portion of the desk top, said hook member comprising a terminal arm for insertion into the hollow marginal portion of the desk top to rest upon the bottom wall of said portion thus to support the weight of the case from said bottom wall, and another arm angularly related to said terminal arm for engagement with a side portion of the desk when said terminal arm is operatively engaged with said bottom wall.
4. An attachment for a desk of the type in which the desk top includes a hollow marginal portion comprising a vertical edge wall and a bottom wall extending inwardly from said edge wall and terminating in spaced relation to the side of the desk, said attachment comprising a case, and a hook member carried by said case for detachable interfitting engagement with the hollow marginal portion of the desk top, said hook member including an arm for insertion into the hollow marginal portion of the desk top to rest upon the bottom wall of said top portion thus to support the weight of the case from said bottom wall.
5. In testimony whereof we hereunto affix our signatures.

JASON A. FITCH.
EDWARD ALBERT PURNELL.
